UNITED STATES PATENT OFFICE.

WOLFGANG SCHRADER, OF BERLIN, GERMANY, ASSIGNOR TO ANTONIUS LOUIS DE BRUYNE, OF HILVERSUM, NETHERLANDS.

PORTABLE RAILWAY-CRANE.

1,068,279.

Specification of Letters Patent. Patented July 22, 1913.

Application filed March 10, 1913. Serial No. 753,255.

To all whom it may concern:

Be it known that I, WOLFGANG SCHRADER, a citizen of the Empire of Germany, residing at Berlin, in the Empire of Germany, have invented a new and useful Portable Railway-Crane, of which the following is a specification.

My invention relates to a novel portable railway-crane with a movable boom pivotally connected by means of three pairs of links with a frame, which is turnable on the carriage around a vertical main pivot.

The portable crane is so constructed, that the boom can be moved forward for work and moved rearward for the transport of the crane. When moved rearward the boom occupies a lowest approximately horizontal position, so that it falls within the compass of a profile or section generally allowed for the passage of any railway train and at the same time it falls within the limits of the outer length of the carriage, so that the portable crane can be coupled direct to any locomotive or inserted in any train without requiring any protecting car to be inserted between it and the locomotive or the neighboring car or cars. By moving forward the boom can be raised into a more or less inclined position; so that the load can be lifted to a convenient height, while the radius of the boom is of course more or less increased. The portable crane may be so constructed, that its boom can be given two different radii and two different lifting heights, so that heavier and lighter weights can be equally well handled. A movable counter-weight is provided for balancing the crane and is so connected with the rear end of the boom by means of ropes or the like, that by moving forward the boom the counter-weight is at the same time moved to the rear outward on slightly ascending rails and that by moving the boom rearward the counter-weight is at the same time by its own weight returned to its initial position. A single windlass is provided in the frame for moving the boom forward and rearward and also for raising and lowering the load. The three pairs of links for connecting the boom with the frame are so disposed, that the rear end of the boom is pivotally connected with the rear pair of links and can slide with its two pivots in longitudinal slots of the middle pair of links. The front

pair of links is at the upper end pivotally connected with the boom between its ends at a point nearer to the rear end. While the front pair of links serves for simply guiding the boom during its motion forward and rearward, the rear pair of links serves for turning the boom during its forward motion into its raised inclined position and during the rearward motion into its lowest approximately horizontal position. The middle pair of links makes with the rear pair, when looked at from a side, a variable triangle, the vertex of which lies in the rear end of the boom. A segment is provided on the carriage and the lower ends of the two links in the rear pair are made to project downward from the pivots, so that they can compass the segment on the carriage for the lowest horizontal position of the boom and thus lock it for preventing the crane from turning on the carriage. For the upper raised position of the boom the said projecting lower ends of the rear links are out of the reach of the segment, so that the boom with the hanging load can be freely turned around the vertical axis of the main pivot. Other features of the invention will be hereinafter set forth and pointed out in the claims.

I will now proceed to describe my invention with reference to the accompanying drawings, in which—

Figure 1 diagrammatically shows the upper part of the novel portable railway-crane, the boom occupying its lowest horizontal position for the minimum radius, only so many parts being shown as is sufficient for the understanding of the invention. Fig. 2 is a similar diagram to show the boom in its middle less inclined position for an intermediate radius. Fig. 3 is a similar diagram to show the boom in its extreme raised inclined position for the maximum radius, Fig. 4 is an elevation of the complete portable railway crane, the boom occupying its extreme raised position for the maximum radius in correspondence with Fig. 3, Fig. 5 is a vertical longitudinal section through the same, the carriage being shown in elevation. Fig. 6 is a front end view of the same, Fig. 7 is an upper view of the same, and Fig. 8 is an upper view of the carriage alone, the vertical main pivot being shown in section.

Similar characters of reference refer to similar parts throughout the several views.

On a suitable carriage 1 are disposed a vertical main pivot 2 (Figs. 5 and 8), a concentric circular rail 3 and a concentric segmental projection 4 serving as a stop. A suitable number of carrying rollers 5 (Fig. 5) adapted to roll on the circular rail 3 are disposed in a suitable carrying frame 6, 10 which is mounted to turn around the main pivot 2. I do not further describe the carriage 1 nor the carrying frame 6, as their construction is immaterial to my invention and may be varied in any known manner.

15 The carrying frame 6 is rigidly connected with a main frame 7 having about the shape of a lying L (Figs. 4 and 5) and shown as made from wrought iron plates and angle-irons. In the horizontal part of the main frame 7 three parallel horizontal rods 8^a, 9^a, 10^a are fastened, the outer ends of which serve as pivots 8, 9, 10. On the front pivots 8, 8 a pair of parallel links 11, 11 is mounted to rock, which at the upper end is pivotally connected with a boom 12 of any known construction by means of its pivots 13, 13 that are shown as formed by the outer ends of a cross rod 14 (Fig. 5) fastened in the boom. The rear end of the boom 12 is provided 30 with a cross shaft 15^a, the outer ends of which serve as pivots 15, 15 that are connected with the rear pivots 10, 10 below by means of a rear pair of parallel links 16, 16. On the middle pivots 9, 9 a third pair of 35 parallel links 17, 17 is mounted to rock, which links are for the upper part provided with longitudinal slots 18, in which the two rear pivots 15, 15 of the boom 12 are guided, so that in this manner the upper ends of the 40 rear links 16, 16 are also pivotally connected with the upper parts of the middle links 17, 17. It is evident, that in the elevation the middle links 17, 17 make with the rear links 16, 16 and the base a triangle, which, in 45 shape varies during the motion of the boom 12 in either direction. For the extreme rear position of the boom 12 shown at Fig. 1 it is nearly horizontal and the pivots 15, 15 bear against the upper ends of the slots 18.

50 For the extreme front position shown at Fig. 3 the boom 12 is most inclined and the pivots 15, 15 bear against the lower ends of the slots 18. Obviously the front links 11, 11 support the boom 12 and guide it during 55 the forward and rearward motion, while the rear links 16, 16 pull the rear end of the boom downward whereby the front end of the same is raised.

The two middle links 17, 17 are about in 60 their middle connected together by means of a rod 19^a (Fig. 5), on the outer ends of which two parallel locks 20, 20 are fastened. Each lock 20 has two superposed hooks 21, 22 and should be pressed rearward in any 65 known manner, so as to bear against the up-

per rear pivots 15. For example the two locks 20, 20 are shown to have each a lower inclined arm 23 with a handle 24. The lower arms 23, 23 are widened so as to serve as weights which press the locks 20, 20 rearward. The rear upper pivots 15, 15 are to engage either in the upper hooks 21 (Fig. 2) or in the lower hooks 22 (Figs. 3 and 4). 70

Within the vertical part of the main frame 7 a suitable windlass 25 (Fig. 5) is disposed, which is shown as comprising a drum 26, a double purchase lifting gear, two winch-handles 27, a strap brake 28 and a lever 29 for same. A suitable block 30 having a long shaft 31 is suspended from the front end of the boom 12 by means of ropes 32, 32 passing on the one hand over a balancing sheave 33 and on the other hand over two sheaves 34 at the front end of the boom 12 and two sheaves 35, 35 loose on the shaft 80 15^a to the drum 26. Two parallel stop plates 36, 36 having each two notches 37, 38 are rigidly connected with the upper end of the boom 12 and serve for checking the upward motion of the block 30, the outer ends of the shaft 31 being capable of engaging either in the front notches 37 (Figs. 1 and 2) or in the rear notches 38 (Fig. 3). 90

The upper side edges of the horizontal part of the main frame 7 are slightly inclined so as to ascend outward and serve as rails for the wheels 39, 39 of a movable counterweight 40. Loose on the shaft 15^a in the rear end of the boom 12 are two parallel links 41, 41, which are connected with 100 the inner end of the counterweight 40 by means of two ropes 42, 42 passing over two guiding pulleys 43, 43 loose on a shaft 44 that is fastened in the rear end of the frame 7. The counterweight 40 is at the rear provided with a hook 45, in which the rod 19^a in the middle pair of links 17, 17 can engage (Fig. 1) for preventing the counterweight 40 from motion during the transport of the crane. Preferably the vertical part of the 110 frame 7 is made so high (Fig. 1) as to support the front part of the boom 12 in its lowest and extreme rear position. Two opposite stops 46, 46 (Fig. 6) are fastened on the upper surface of this front frame part 115 for preventing the boom 12 from lateral motion during the transport of the crane. The said vertical part of the frame 7 is preferably made horizontally so long (Fig. 4) as to bear against the inner sides of the two front links 11, 11 for preventing the boom 12 from shaking during its revolution around the main pivot 2. The rear links 16, 16 are so much lengthened downward from the pivots 10, 10 as to be capable of bearing 120 against the two end faces of the segmental stop 4 (Fig. 8) for the lowest and extreme rear position of the boom (Fig. 1) so as to prevent the crane from turning on the carriage 1 during the transport. A suitable 125

137

platform 46^a may be provided on the main frame 7 for supporting the workmen.

The portable railway-crane described operates as follows: As already mentioned 5 above, the boom 12 normally occupies its lowest and extreme rear position shown at Fig. 1, the outer ends of the shaft 31 of the block 30 engaging in the front notches 37 of the stop plates 36, so that the transportable 10 crane can be coupled to any locomotive or train and therewith moved to the respective place for work without encountering any obstacle since its boom is within the compass of a profile or section generally allowed for 15 the passage of any train. When it is desired to raise and move forward the boom 12 into the middle position for the intermediate radius indicated at Fig. 2 and to handle heavier loads, first the two winch- 20 handles 27, 27 are turned in the hoisting direction. As the outer ends of the shaft 31 of the block 30 engage in the front notches 37 of the stop plates 36, 36 and are thus prevented from upward motion relatively to 25 the boom 12 and only the two ropes 32, 32 between the two rear sheaves 35, 35 and the drum 26 (Fig. 5) are capable of being shortened, the consequence of the revolution of the two winch-handles 27, 27 will be to pull 30 the boom 12 forward while turning its rear end downward and its front end upward. Then the upper hooks 21 of the two locks 20, 20 will soon strike the rear pivots 15, 15 of the boom and ride over them, until the 35 pivots 15, 15 slide beneath the lower ends of the upper hooks 21, which then snap behind them, the two locks 20, 20 turning downward. Thereupon the two winch-handles 27, 27 are turned in the opposite direction 40 or may be released while the brake lever 29 is operated for allowing the pivots 15, 15 to fully engage in the upper hooks 21 (Fig. 2). When the brake 28 is further released, 45 the boom 12 will not any more alter its position but the block 30 will simply lower, as it is no longer checked by the two stop plates 36, 36. The counterweight 40 has meanwhile been liberated by the cross shaft 19^a of the middle pair of links 17, 17 moving out of its hook 45 and then drawn outward by means of the two links 41, 41 and the two ropes 42, 42 and will now occupy its 50 middle position shown at Fig. 2. At the same time the lower ends of the rear links 55 16, 16 will have moved out of the reach of the segmental stop 4, so that the crane can now turn on the carriage 1 around the main pivot 2 in either direction. The load to be lifted is then attached to the double hook 60 of the block 30, whereupon the two winch-handles 27, 27 are turned in the hoisting direction, so that the block 30 will rise and lift the load to the desired height, whereupon the boom 12 with all the movable parts 65 connected therewith can be turned around

the main pivot 2 in the desired direction. When it is desired to further raise the "cat-head" and to move the boom 12 into the extreme front position for the maximum radius shown at Figs. 3 to 5, then the two 70 winch-handles 27, 27 are turned in the hoisting direction, until the outer ends of the shaft 31 of the block 30 engage in the front notches 37 of the two stop plates 36, 36, and the rear end of the boom 12 is 75 so much pulled downward, that the pivots 15, 15 move out of the upper hooks 21 and slide first on the rear edges of the locks 20, 20, then on the backs of the two lower hooks 22, whereupon the latter snap behind them. 80 At this moment the two winch-handles are either turned in the other direction or released while the brake lever 29 is operated for permitting the pivots 15, 15 to fully engage in the lower hooks 22, whereupon the outer ends of the block shaft 31 move out 85 of the front notches 37 of the two stop plates 36, 36 and the crane will be ready for work. At this moment the wheeled counterweight 40 will occupy its extreme outer position 90 shown.

In order to return all the parts of the crane into the initial position, first the two winch-handles 27, 27 are turned in the hoisting direction, until the outer ends of the 95 block shaft 31 engage in the rear notches 38 of the two stop plates 36, 36 (which notches are now about in the vertical plane of the shaft 31, as can be seen from Figs. 3 to 5) and the two pivots 15, 15 move downward 100 in the slots 18 of the rear links 17, 17 out of the reach of the lower hooks 22, whereupon the handles 24, 24 are moved to the rear for turning the two stops 20, 20 to the front (that is to the left in Figs. 3 to 5) and the 105 two winch-handles 27, 27 are turned in the opposite direction or released while using the brake 28, as the case may be. It is to be borne in mind, that the over-weight of the boom 12 (its center of gravity being on the 110 front side of the pivots 13, 13) tends to press the two rear pivots 15, 15 upward in the slots 18 of the two middle links 17, 17. When the two pivots 15, 15 have moved upward out of the reach of the lower hooks 22, the two 115 handles 24, 24 are released, so that the two pivots 15, 15 now slide on the rear edges of the two stops 20, 20 and engage in the two upper hooks 21. At this moment the two outer ends of the block shaft 31 will move 120 out of the rear notches 38 of the two stop plates 36, 36 into the vertical plane of the front notches 37 (Fig. 2). Then the two winch-handles 27, 27 are again turned in the hoisting direction, so that the outer ends of 125 the block shaft 31 engage in the front notches 37 of the two stop plates 36, 36 and the two rear upper pivots 15, 15 move downward in the slots 18 of the middle links 17, 17 out of reach of the upper hooks 21, where- 130

upon the two handles 24, 24 are moved to the rear for turning the two locks 20, 20 forward and the two winch-handles 27, 27 are turned in the opposite direction or released 5 while using the brake 28, so that the rear pivots 15, 15 move upward in the slots 18 of the links 17, 17 and the boom 12 sinks into the lowest and extreme rear position shown at Fig. 1.

10 The portable railway-crane can be varied in many respects without departing from the spirit of my invention.

I claim:

1. In a portable crane, a carriage, a frame 15 on said carriage having three parallel pairs of opposite pivots, a boom having at the rear end a rear pair of opposite pivots and intermediate the ends a middle pair of opposite pivots, a rear pair of links rocking 20 on the rear pair of pivots of said frame and pivotally connected with the rear pair of pivots of said boom, a front pair of links rocking on the front pair of pivots of said frame and pivotally connected with the middle 25 pair of pivots of said boom, a middle pair of links rocking on the middle pair of pivots of said frame and being for the upper part adapted to longitudinally guide the rear pivots of said boom, and means for 30 varying the distance between the rear pair of pivots of said boom and the front pair of pivots of said frame, whereby said boom is moved rearward into a lowest position for the minimum radius or moved forward into 35 a higher or highest position for an intermediate or the maximum radius.

2. In a portable crane, a carriage, a frame 40 on said carriage having three parallel pairs of opposite pivots, a boom having at the front end a pair of notched stop plates, at the rear end a rear pair of opposite pivots and intermediate the ends a middle pair of opposite pivots, a rear pair of links rocking 45 on the rear pair of pivots of said frame and pivotally connected with the rear pair of pivots of said boom, a front pair of links rocking on the front pair of pivots of said frame and pivotally connected with the middle pair of pivots of said boom, a middle 50 pair of links rocking on the middle pair of pivots of said frame and being for the upper part adapted to longitudinally guide the rear pivots of said boom, a block comprising sheaves and a shaft adapted to engage in 55 the notches of said stop plates and to be thereby checked in the upward motion, sheaves at both ends of said boom, a drum in said frame, drawing means passing from the front end of said boom around the 60 sheaves of said block and over the sheaves at both ends of said boom to the front to said drum, means for longitudinally adjusting the rear pivots of said boom on said middle pair of links, and means for turning 65 said drum in either direction so as to raise

and lower the load when said block is free of said stop plates or to move said boom rearward into a lowest position for the minimum radius or forward into a higher or highest position for an intermediate or maximum radius, when the shaft of said block engages in the notches of said stop plates.

3. In a portable crane, a carriage, a frame 70 on said carriage having three parallel pairs of opposite pivots, a boom having at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle 75 pair of links rocking on the middle pair of pivots of said frame and having for the upper part longitudinal slots in which the rear pivots of said boom are guided, and means for varying the distance between the rear pair of pivots of said boom and the front pair of pivots of said frame, whereby said boom is moved rearward into a lowest position for the minimum radius or moved forward into a higher or highest position 80 for an intermediate or the maximum radius.

4. In a portable crane, a carriage, a frame 85 on said carriage having three parallel pairs of opposite pivots, a boom having at the front end a pair of notched stop plates, at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle 90 pair of links rocking on the middle pair of pivots of said frame and having for the upper part longitudinal slots in which the rear pivots of said boom are guided, a block comprising sheaves and a shaft adapted to engage in the notches of said stop plates and to be thereby checked in the upward motion, 95 sheaves at both ends of said boom, a drum in said frame, drawing means passing from the front end of said boom around the sheaves of said block and over the sheaves 100 at both ends of said boom to the front to said drum, means for adjusting the rear pivots of said boom in the longitudinal slots of said middle pair of links, and means for turning said drum in either direction so as 105 to raise and lower the load when said block is free of said stop plates or to move said boom rearward into a lowest position for the minimum radius or forward into a higher or highest position for an intermediate 110 or the maximum radius.

5. In a portable crane, a carriage, a frame 115 on said carriage having three parallel pairs of opposite pivots, a boom having at the front end a pair of notched stop plates, at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle 120 pair of links rocking on the middle pair of pivots of said frame and having for the upper part longitudinal slots in which the rear pivots of said boom are guided, a block comprising sheaves and a shaft adapted to engage in the notches of said stop plates and to be thereby checked in the upward motion, sheaves at both ends of said boom, a drum in said frame, drawing means passing from the front end of said boom around the sheaves of said block and over the sheaves 125 at both ends of said boom to the front to said drum, means for adjusting the rear pivots of said boom in the longitudinal slots of said middle pair of links, and means for turning said drum in either direction so as to raise and lower the load when said block is free of said stop plates or to move said boom rearward into a lowest position for the minimum radius or forward into a higher or highest position for an intermediate 130 or the maximum radius.

diate or maximum radius, when the shaft of said block engages in the notches of said stop plates.

5. In a portable crane, a carriage, a frame turnable on said carriage around a vertical axis and having three parallel pairs of opposite pivots and two parallel inclined rails ascending outward, a boom having at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle pair of links rocking on the middle pair of pivots of said frame and being for the upper part adapted to longitudinally guide the rear pivots of said boom, means for varying the distance between the rear pair of pivots of said boom and the front pair of pivots of said frame so as to move said boom rearward into a lowest position for the minimum radius or forward into a higher or highest position for an intermediate or the maximum radius, a wheeled counterweight rolling on the inclined rails of said frame, guiding pulleys at the rear end of said frame, and drawing means connecting the rear end of said boom with said counterweight and passing over said guiding pulleys.

6. In a portable crane, a carriage, a frame turnable on said carriage around a vertical axis and having three parallel pairs of opposite pivots and two parallel inclined rails ascending outward, a boom having at the front end a pair of notched stop plates, at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of links rocking on the middle pair of pivots of said frame and being for the upper part adapted to longitudinally guide the rear pivots of said boom, a block comprising sheaves and a shaft adapted to engage in the notches of said stop plates and to be thereby checked in the upward motion, sheaves at both ends of said boom, a drum in said frame, drawing means passing from the front end of said boom around the sheaves of said block and over the sheaves at both ends of said boom to the front to said drum, means for longitudinally adjusting the rear pivots of said boom on said middle pair of links, means for turning said drum in either direction so as to raise and lower the load when said block is free of said stop plates.

or to move said boom rearward into a lowest position for the minimum radius or forward into a higher or highest position for an intermediate or maximum radius, when the shaft of said block engages in the notches of said stop plates, a wheeled counterweight rolling on the inclined rails of said frame, guiding pulleys at the rear end of said frame, and drawing means connecting the rear end of said boom with said counterweight and passing over said guiding pulleys. 70 75

7. In a portable crane, a carriage, a frame on said carriage having three parallel pairs of opposite pivots, a boom having at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle pair of links rocking on the middle pair of pivots of said frame and being for the upper part adapted to longitudinally guide the rear pivots of said boom, and means for varying the distance between the rear pair of pivots of said boom and the front pair of pivots of said frame, whereby said boom is moved rearward into a lowest position for the minimum radius or moved forward into a higher or highest position for an intermediate or the maximum radius, said frame being adapted to support the front part of said boom in its lowest position and to prevent it from lateral motion.

8. In a portable crane, a carriage, a frame turnable on said carriage around a vertical axis and having three parallel pairs of opposite pivots, a boom having at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle pair of links rocking on the middle pair of pivots of said frame and being for the upper part adapted to longitudinally guide the rear pivots of said boom, and means for varying the distance between the rear pair of pivots of said boom and the front pair of pivots of said frame, whereby said boom is moved rearward into a lowest position for the minimum radius or moved forward into a higher or highest position for an intermediate or the maximum radius, said frame being adapted to support the front part of said boom in its lowest position and to bear against the inner sides of said two front 130

- links for preventing said boom in its highest position from shaking during the rotation of the carriage around the vertical axis.
9. In a portable crane, a carriage, a frame 5 on said carriage having three parallel pairs of opposite pivots and two parallel inclined rails ascending outward, a boom having at the rear end a rear pair of opposite pivots and intermediate the ends 10 a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle pair of links 15 rocking on the middle pair of pivots of said frame and being for the upper part adapted 20 to longitudinally guide the rear pivots of said boom, means for varying the distance between the rear pair of pivots of said boom and the front pair of pivots of said frame, whereby said boom is moved rearward into 25 a lowest position for the minimum radius or moved forward into a higher or highest position for an intermediate or the maximum radius, a wheeled counterweight rolling 30 on the inclined rails of said frame and provided at the outer end with a hook, guiding pulleys at the rear end of said frame, drawing means connecting the rear end of said boom with said counterweight and passing over said guiding pulleys, and a cross 35 rod between said middle links adapted to engage in the hook of said counterweight for the lowest position of said boom so as to prevent said counterweight from motion during the transport of the crane.
10. In a portable crane, a carriage, a frame turnable on said carriage around a vertical axis and having three parallel pairs of opposite pivots, a boom having at the rear end a rear pair of opposite pivots and intermediate the ends a middle pair of opposite pivots, a rear pair of links rocking on the rear pair of pivots of said frame and pivotally connected with the rear pair of pivots of said boom, a front pair of links rocking on the front pair of pivots of said frame and pivotally connected with the middle pair of pivots of said boom, a middle pair of links rocking on the middle pair of pivots of said frame and being for the upper part adapted to longitudinally guide the rear pivots of said boom, means for varying the distance between the rear pair of pivots of said boom and the front pair of pivots of said frame, whereby said boom is moved rearward into a lowest position for the minimum radius or moved forward into a higher or highest position for an intermediate or the maximum radius, and a stop on said carriage, said rear links being so much lengthened downward beyond the rear pivots of said frame as to compass said stop for the lowest position of said boom so as to prevent the crane from turning on said carriage during the transport, while by moving said boom forward the lower lengthened ends of said rear links are moved out of the reach of said stop for permitting the crane to turn.

WOLFGANG SCHRADER.
